ELECTRIC PUMP

Application filed February 16, 1927. Serial No. 168,630.

This invention relates to pumps and particularly to pumps for use as compressors for mechanical refrigerating systems.

Heretofore, it has been common to construct a pump or compressor with a piston or compression element movable within a cylinder or compression chamber and actuated through a connecting member, such as a piston rod, extending through the outer casing or cylinder head. The opening in the outer casing or cylinder head between the actuating element, such as the piston rod, has been filled by packing. It has been difficult, and in fact impossible, to provide packing for this purpose which would give long continued efficient service without permitting leakage.

It is an object of the present invention to provide a pump or compressor in which such difficulties are minimized or eliminated and such that when used as a compressor for compressing refrigerants the damage caused to the parts of the compressor or pump by leakage of the refrigerant is minimized. With this in view the invention particularly contemplates the provision of a pump or compressor in which the compression element is wholly enclosed within the compression chamber and actuated in such a manner that there are no moving parts extending from the interior to the exterior of the compression chamber thereby greatly simplifying the packing problems.

These and other objects of the invention will be more clearly understood from the following description in conjunction with the accompanying drawings, in which:

Fig. 1 is a longitudinal sectional elevational view of a pump or compressor embodying the invention.

Fig. 2 is a plan view of the same partly in section.

Figs. 3 and 4 are longitudinal sectional elevational and plan views respectively of the same illustrating the position of the various parts during movement of the compression element or piston.

Fig. 5 is a longitudinal sectional elevational view of the same showing the arrangement of parts when the compression element is at one end of its stroke; and

Fig. 6 is a sectional elevational view taken upon the line 6—6, of Fig. 2.

The pump or compressor specifically illustrated in the drawings comprises a cylinder casing 10 providing a compression chamber 11 and is provided with an intake opening or port 12 near the central portion thereof. The outer surface of the casing is provided with a flat portion to which plates 13 are secured as by screws 48, said plates providing suitable slideways 14 for a slide referred to more fully hereinafter.

The ends of the cylinder are entirely closed by heads 15 secured to the cylinder by bolts 16 engaging flanges 17 at the ends of the cylinder. Each cylinder head is formed with a relatively large portion 18 and a reduced central portion 19. The cylinder heads are provided with aligned axial bores 20 constituting guides for a pair of aligned piston rods 21 projecting in opposite directions from the opposite faces of a piston 22. Each piston rod is provided with an annular groove 23 adjacent the face of the piston. An annular groove 24 is provided in each cylinder head within the bore 20 and communicates directly with an exhaust port or opening 25. The reduced portion 19 of each cylinder head is enclosed by the coil 26 of the electro-magnetic device or solenoid of which the reduced portion 19 of the cylinder head constitutes the core and the enlarged portion 18 a pole piece, the cylinder heads being composed of suitable electro-magnetic material such as soft iron. The coil 26 is suitably held in place against the portion 18 of the cylinder head by a plate 27 secured to the cylinder head in any suitable manner as by screws 28. A by-pass opening 29 extends through the piston 22 and the piston rods 21 so as to permit the flow of fluid between the bores 20 during movement of the piston.

The electro-magnetic devices are energized from any suitable source of electric current, such as a battery 30, one terminal of which is grounded, as indicated at 31, and the other terminal of which is connected with the coil 26 at the right by a conductor 32. A conductor 33 leads from the coil 26 to the contact post 34 of an electric switch. The circuit

is grounded through the cylinder casing and parts described later. The coil 26 at the left is connected to the battery 30 by a conductor 35 and to the contact post 36 of the switch by a conductor 37. The contact posts 34 and 36 are set in suitable insulators 38 so that their top surfaces are flush with the outer flat portion of the cylinder.

In order that the electro-magnetic devices 10 may be alternately energized and de-energized to reciprocate the piston within the cylinder, an automatically operated switch is provided adapted to complete the break alternately the circuits leading from the battery 15 30. A suitable switch for this purpose may comprise a slide 53 operating in the slideways 14 and having its ends arranged in proximity to the pole pieces 18 of the solenoids, whereby said slide is permitted a limited reciprocatory 20 movement in said slideways between said pole pieces. The slide 53 is provided with an opening 25 providing slideways 54 engaged by a second slide 55 of suitable insulating material having openings 56 to receive suitable electrical contacts 57 and 58 which are yieldingly held against the outer flat portion of the casing 10 by a leaf spring 59 engaging the outer ends of the contacts 57 and 58 and adjustably mounted upon the slide 55 by a screw 60. A 30 spring 61 is secured to the slide 55 and extends to and is secured to posts 62 upon the slide 53 in order to move the slide 55 as explained hereinafter in response to movements of the slide 53.

35 The movements of the latter slide in its slideways 14 are retarded by a dash-pot device comprising a plunger 45 operating in a cylinder 46 formed in a casing 47 having ears 49 secured to one of the plates 13, as by the 40 screws 48 which secure said plates to the flat portion of the casing 10. The plunger 45 is connected with the slide 53 by an arm 51 projecting from said plunger through a slot 50 in the wall of the casing 47. A by-pass 63 is 45 provided in the wall of the casing 47 leading to opposite ends of the cylinder 46 to permit the flow of a suitable fluid, such as glycerine, during movement of the plunger 45. An adjusting screw 64 serving as a valve is provided in the casing 47 to control the flow of 50 fluid through the by-pass 63.

55 A pair of movable stop arms 65 and 66 are slidably mounted within openings 67 in lugs 68 projecting from the other plate 13. The stop arm 65 is provided with a pin 70 and the stop arm 66 is provided with a similar pin 71 projecting therefrom and between said pins and the faces of the lugs 68 are interposed springs 72 surrounding said arms. The outer end of each of the stop arms 65 and 66 is provided with a pin 73 projecting therefrom to engage the outer face of the lugs 68 and thereby limit the inward movement of the arms as actuated by the springs 65

72. The stop arm 65 is so positioned as to move inwardly within the path of and engage one end of the slide 55 when the contact 57 engages the post 36, and the stop arm 66 is so positioned as to move inwardly in response to the action of the spring 72 to engage the opposite end of the slide 55 when it has been moved to a position such that the contact 58 engages the post 34. The position and movement of the stop arms 65 and 66 is controlled by positioning the pins 70 and 71 thereon within the paths respectively of the cams 74 and 75 mounted upon the slide 53.

In the construction illustrated, one of the contacts 57 and 58 will always be held in engagement with one of the contact posts 34 and 36. As illustrated in Figs. 1 to 4 the contact 57 is held in engagement with the contact post 36 by the stop arm 65 engaging the end of the slide 55. It will be noted that the electrical circuit is completed through the spring 59, contact 58, and casing 10 which is grounded as indicated at 76. When thus positioned the solenoid coil at the left is energized, thereby causing its pole piece 18 to attract the slide 53 and tending to move the latter toward the left, this movement being retarded by the dash pot plunger 45. This movement of the slide 53 supplies the spring 61 with potential energy tending to move the slide 55 in the same direction, the latter slide, however, being at this time held against such movement by the stop 65. The relative positions of the plunger 45, slides 53 and 55, and spring 61 during such movement are illustrated by a comparison of Figs. 2 and 4. The device is so constructed and arranged that when the piston 22 has reached the end of its stroke (as viewed in Fig. 5) the cam 74, which moves in unison with the slide 53, as retarded by the plunger 45, is brought to a position such as to engage the pin 70 and withdraw the stop arm 65 from the slide 55 and permit the latter to be moved to the left by the spring 61.

100 This movement of the slide 55 brings the contact 58 into engagement with the contact post 34 thereby completing the electrical circuit through the solenoid coil on the right (as viewed in Fig. 5). At the same time the stop arm 66 is moved inwardly due to the action of the spring 72 to engage the end of the slide 55 and prevent its movement toward the right. It will be understood that the solenoid coil on the right now is energized and the slide 53, as well as the piston 22, is drawn to the right against the retarding influence of the plunger 45. When the piston has moved towards the right to reach the end of its stroke the cam 75, which is also moving toward the right in unison with the slide 53, will engage the pin 71 to depress the stop arm 66 and release it from engagement with the slide 55 whereupon the latter will move toward the right so as to bring the 110 115 120 125 130

contact 57 again into engagement with the contact post 36. These operations are alternately taking place to energize first one solenoid coil and then the other to reciprocate the piston 22 back and forth. The arrangement is such that when the piston is at the end of its stroke a suitable refrigerant is permitted to pass into the cylinder through the inlet port 12 and undergoes compression until the annular groove 23 on the piston rod 21 is brought beneath the annular groove 24 whereupon the refrigerant is permitted to expand rapidly by escaping through the exhaust port 25.

15 It will be observed that the mechanism described provides means, located wholly outside the pump cylinder, for controlling the movements of the piston within the latter, there being no mechanical connections between the piston and its controlling means extending through the wall of the cylinder, the latter, except for the inlet and exhaust ports, being completely closed, thereby obviating all leakage and packing problems.

20 25 It will also be seen that the same solenoids are employed for actuating both the pump piston and the controlling switch, thereby resulting in an exceedingly simple, compact, and inexpensive construction.

30 What I claim is:

1. In a pump, in combination, a pump cylinder having an inlet and an outlet port, a cylinder head entirely enclosing each end of the cylinder, a piston reciprocable within the cylinder, an electro-magnetic device for moving the piston in each direction, an electrical supply source, a pair of spaced contact posts each electrically connected with one of the electro-magnetic devices, a pair of reciprocable slides actuated in response to the action of the electro-magnetic devices, one of said slides carrying a pair of contacts adapted to engage said posts alternately to complete the circuit from said supply source through the electro-magnetic devices, and means for holding said contact carrying slide to complete the circuit through one electro-magnetic device until the piston has completed its stroke and then permit it to move to complete the circuit through the other.

2. In a pump, in combination, a pump cylinder having an inlet and an outlet port, a cylinder head entirely enclosing each end of the cylinder, a piston reciprocating within the cylinder, an electro-magnetic device for moving the piston in each direction, an electrical supply source, a pair of spaced contact posts each connected with an electro-magnetic device, a reciprocating slide carrying a pair of contacts adapted to engage said posts alternately, a second slide reciprocated in response to the action of said electro-magnetic devices and resiliently connected with the first slide, a stop for preventing movement of the first slide with the second, and

a cam carried by the second slide adapted to release said stop to permit movement of the first slide when the piston nears the end of its stroke.

3. In a pump, in combination, a cylinder, a piston therein, electromagnetic means for reciprocating said piston in said cylinder, a switch for controlling the flow of current to said electromagnetic means, an actuator for said switch actuated by said electromagnetic means, a spring connecting said actuator and switch, means controlled by said actuator for restraining said switch, and means for retarding the movements of said actuator.

4. In a pump, in combination, a cylinder, a piston therein, a pair of solenoids for reciprocating said piston in said cylinder, said solenoids having pole pieces, a switch for controlling the flow of current to said solenoids, a slide guided on the exterior of said cylinder for reciprocation between said pole pieces and subjected to the attraction thereof, a spring connecting said slide and switch, detents for restraining said switch, said detents being controlled by said slide, and a dash pot mechanism for retarding the movements of said slide under the attraction of said pole pieces.

5. In an electro-magnetic reciprocating mechanism, in combination, a magnetic plunger, two solenoids for reciprocating said plunger, and a switch mechanically separate from said plunger and actuated by magnetic attraction induced by the energization of said solenoids for directing the flow of electric current to said solenoids alternately.

6. In an electro-magnetic reciprocating mechanism, in combination, a magnetic plunger, two solenoids for reciprocating said plunger, said solenoids having fixed pole pieces, and a switch mechanically separate from said plunger and actuated by the attraction of said pole pieces when said solenoids are energized for directing the flow of current to said solenoids alternately.

7. In an electro-magnetic reciprocating mechanism, in combination, a magnetic plunger, two solenoids for reciprocating said plunger, said solenoids having fixed pole pieces, a switch mechanically separate from said plunger and actuated by the attraction of said pole pieces when said solenoids are energized for directing the flow of current to said solenoids alternately, and mechanism for retarding the movements of said switch.

8. In an electromagnetic reciprocating mechanism, in combination, a magnetic plunger, electromagnetic means for reciprocating said plunger, a switch for controlling the flow of current to said electromagnetic means, and means actuated by the magnetic field surrounding said plunger for operating said switch.

9. In an electromagnetic reciprocating mechanism, in combination, a magnetic

plunger, two solenoid windings for reciprocating said plunger, a switch mechanically separate from said plunger for directing the flow of electric current to said solenoids alternately, and means actuated by the magnetic field surrounding said plunger for operating said switch.

In testimony whereof I affix my signature.
HARRY H. COBE.
